COMPRESSED AIR SUPPLY SYSTEM

Kenneth A. Alexander, Forest Hills, Pa., assignor
to Westinghouse Air Brake Company, a corpora-
tion of Pennsylvania

Application November 29, 1950, Serial No. 198,065

2 Claims. (CL. 230—1)

1

This invention relates to a compressed air supply system and more particularly to a compressed air supply system comprising novel means for storing and removing moisture from the compressed air.

A prime object of the invention is to provide a small, compact portable unit for compressing air including means for storing the compressed air and removing the moisture from same.

Other objects and advantages will become apparent from the following more detailed description of the invention taken in connection with the accompanying drawing in which:

Fig. 1 is an elevation view in outline of a commercial form of air compressing apparatus embodying the invention; and

Fig. 2 is a schematic representation, of the same apparatus, partly in outline and partly in section.

Description

Referring to Figs. 1 and 2, the air compressing apparatus comprises an air compressor device 1 driven by an electric motor 2 via such as a V-belt 3. An aftercooler 4, in the form of continuous coils 5 of copper tubing for example, is connected to the compressor device 1 to receive the discharge of the warm compressed air therefrom. Circulation of the warm discharged compressed air will be cooled in the usual manner in passing through the aftercooler coils and in thus being cooled, will lose much of its moisture in the form of condensate which collects on the inner walls of the coils.

According to a feature of the invention, the continuous aftercooler coils 5 are disposed around a vertical axis with the discharge of compressed air from the compressor entering from the top and leaving at the bottom via such as a delivery pipe 6 connected thereto by means of a coupling 7. By virtue of the vertical arrangement of the aftercooler 4, condensate condensing on the inner walls of the coils 5 will flow to the bottom. For collecting such condensate at the bottom of the aftercooler 4 an additional collecting coil 8 is added to the aftercooler in substantial symmetry with the coils 5. The coil 8 joins the bottom of the lowermost end of the continuous coils 5 preferably at a point preceding the coupling 7 to assure that condensate will drop into the condensate collecting coil 8 rather than continue into the delivery pipe 6. A two-way cock 9 is connected to the lowermost discharge end of the collecting coil 8, which cock in the position in which it is shown in the drawing connects said discharge end to a blowdown valve device 10 via a pipe 11, or in another position, will connect said discharge end directly to the atmosphere via a port 12.

The aftercooler coils 5 also act as a small volume reservoir for storing the compressed air from the compressor 1 and the delivery pipe 6 is connected to a four way union fitting 14 which also connects to a supply pipe 15 for connection to a device or devices (not shown) to utilize fluid

2

under pressure, to a safety valve device 16 and to a pressure switch device 17 via a pipe 18.

The safety valve 16 may be of any well-known type, as for example it may comprise a spring loaded valve 16a which will unseat should the pressure of the compressed air acting on said valve become excessive.

The pressure switch device 17 carries the blowdown valve device 10 as shown in Fig. 1 and for sake of illustration, schematically may comprise a cylinder 19 in which is slidably disposed a piston 20 subject opposingly to pressure of fluid in a pressure chamber 21 at one side and to force of a compression spring 22 in a spring chamber 23 on its opposite side. The pressure chamber 21 is connected to the pipe 18 and the spring chamber 23 is constantly open to atmosphere via a port 24.

A rod 26 is attached to the piston 20 for reciprocal movement therewith. The rod 26 extends through the spring chamber 23 and outwardly through an accommodating opening in the casing. The outermost projecting end of the rod 26 carries a switch plate 28 of electrical conducting material attached to the rod via non-conducting material 30. Two spaced apart electrical contact elements 32 and 34 are fixed in the path of travel of the switch plate 28. One contact element 34 is connected via a wire 35 to one motor terminal 36, the opposite terminal 37 of which motor may be connected to ground via a wire 38. The other contact element 32 may be connected via a wire 40 to one pole of a battery 41, the opposite pole of which battery may be grounded via a wire 42.

When the pressure of the compressed air in coils 5 and pipe 18 drops to a chosen low value, such pressure as felt in chamber 21 in the pressure switch device 17 will allow the spring 22 to move the piston 20 in the direction of said chamber until the switch plate 28 engages the contact elements 32 and 34 to complete electrical circuit to the motor 2 for operating same and thereby running the compressor 1 to bring the pressure of the compressed air up to a desired value. When such a desired value is shortly reached, this increased pressure of compressed air as felt in chamber 21 will cause movement of the piston 20 in the direction of chamber 23, and through resultant movement of rod 26, will unseat the switch plate 28 from contact elements 32 and 34 to interrupt the electrical circuit to the motor 2, stopping same and thereby stopping the compressor 1.

The blowdown valve device 10, schematically, may comprise a casing 50 having an inlet chamber 51 connected to the pipe 11 and an exhaust chamber 52 open to atmosphere via ports 57 and separated from chamber 51 by a partition 53. A pair of valves 54 and 55 are provided for controlling communication between chambers 51 and 52, respectively, via an opening 56 through partition 53 which extends between these chambers. Respective seats are formed in partition

53 encircling opposite ends of the opening 56 to accommodate the valves 54 and 55. The valves 54 and 55 are connected one to the other by way of a stem 60 extending with clearance through opening 56. The length of the stem 60 relative to the length of opening 56 is such that both valves may not be closed at any one time. A bias spring 61 in chamber 51 is arranged to urge the valves 54 and 55 toward seated and unseated positions, respectively. A stem 62 attached to valve 55 extends through chamber 52 and outwardly of the casing 50 to act as a medium whereby both attached valves 54, 55 may be actuated simultaneously.

According to another feature of the invention, the stem 62 is arranged to be actuated by the pressure switch device 17 to allow the condensate collected in coil 8 momentarily to be blown out to atmosphere each time the compressor 1 is started or stopped.

According to the above feature, a rigid actuating element 70 is attached to the rod 26 of device 17 for reciprocable movement therewith. The element 70 is arranged to extend transversely from the rod 26 into abutting contact with the stem 62 of device 10. By virtue of such arrangement, as the rod 26 moves to terminate operation of the compressor device 1 by interrupting the electrical circuit to motor 2, the actuating element 70 carried by stem 26 will consecutively unseat and seat valves 54 and 55, respectively. After valve 54 has been unseated and valve 55 is yet to be seated, chamber 51 is open to exhaust chamber 52 via opening 56, so that the compressed air in the aftercooler coils 5 will cause condensate collected in the lowermost collecting coil 8 to be blown out to atmosphere via valve device 9, pipe 11, chamber 51, said opening 56, chamber 52 and ports 57. Such blowdown of condensate is temporary as terminated by subsequent closure of the valve 55 and will not allow such release of compressed air from the coils 5 as will materially reduce the pressure of such air stored therein.

When the rod 26 of switch device 17 moves in the direction to cause operation of the compressor device 1 by establishing electrical circuit to the motor 2, the actuating element 70 in moving with said rod 26 will allow the spring 61 in device 10 to consecutively unseat and seat valves 55 and 54, respectively. Again during the time that both valves are unseated and prior to seating of the valve 54, compressed air from the aftercooler coils 5 will blow out the condensate collected in the collecting coil 8 via the valve device 9, pipe 11, and in device 10, the chamber 51, opening 56, chamber 52 and ports 57. Subsequent closure of the valve 54 limits the amount of compressed air from coils 5 utilized for such condensate blowout to a very small amount.

In Fig. 1, 65 designates a base plate upon which the motor 2 and compressor 1 are mounted at opposite ends with the coils 5 and 8 at one side of the compressor and all other parts of the apparatus between said motor and said compressor and coils, thereby providing a very compact portable arrangement.

Summary

It will now be seen that I have provided air compressing apparatus which is compact, particularly in that the aftercooler coils of tubing are used as a volume reservoir for storing the compressed air and in that the lowermost coil or coils of the same tubing connected in sym-

metry to the aftercooler coils is or are employed for collecting condensate, and which comprises improved means for automatic blow out of such condensate with use of only a small amount of compressed air.

Having now described my invention, what I claim as new and desire to secure by Letters Patent is:

1. A compressed air supply system comprising a base plate, an air compressor and a continuous series of pipe coils arranged side by side transversely of said base plate adjacent one end thereof, said pipe coils being arranged in form of a helix with its axis vertical to permit gravity drainage of condensate in the coils and with the uppermost end of said coils open to the discharge of said compressor, a motor for operating said compressor mounted on said plate adjacent the opposite end thereof, a pipe fitting connected to 10 said coils intermediate the uppermost end and the lowermost end thereof for connection with a compressed air using device or the like, a motor control device connected to receive compressed air from said coils via said pipe fitting for starting and stopping said compressor in response to chosen low and high pressures of such air, a blow-off device connected to the lowermost end of said coils to receive condensate accumulated therein, and means operative by said control device in starting or stopping said motor to 20 actuate said blow-off device to open and then close a communication between said coil and atmosphere.
2. Air compressing apparatus comprising an air compressor, a source of electrical energy, a motor operatively connected to said compressor, switch means operable to establish and disestablish electrical circuit between said source and said motor, a series of continuous aftercooler coils connected at their one end to said compressor to receive compressed air discharged therefrom and adapted at their opposite end for delivery of said compressed air, said aftercooler coils being arranged about a vertical axis, a condensate collecting coil connected to the lowermost end of said aftercooler coils, blow-down valve means connected to the outlet end of said collecting coil comprising double seat valve means movable a certain distance to either of two opposite seated positions to vent said collecting coil to atmosphere during such valve movement, and comprising a valve stem operatively connected to said valve means to act as a medium through which said valve means may be actuated, cylinder means comprising pressure responsive means movable said certain distance in opposite directions according to establishment and disestablishment of a certain pressure of compressed air, rigid connecting means operatively connecting said pressure responsive means to said switch means to open and close same upon said establishment and disestablishment, respectively, and other connecting means carried by said rigid connecting means to actuate said valve stem said certain distance in opposite directions.
